HANDBAG

Violet E. Ohlsen, Washington, D. C.

Application April 10, 1942, Serial No. 438,413

2 Claims. (Cl. 150—34)

1

The present invention relates to improvements in pocketbooks or handbags adapted to contain various personal belongings or paraphernalia in compact and readily accessible manner.

Manufacturers of handbags or pocketbooks are continually striving to produce a multiple compartment general purpose handbag satisfactory to women. Many such handbags have been patented but have not proven satisfactory. Some of the chief objections are, inefficient or poor arrangement of parts, lack of compactness, and the fact that they have been limited in usefulness to certain specific purposes; e. g., purely as pocketbooks. The feature of general or multiple utility is quite desirable in many instances, and one which comes readily to mind is in connection with the present national emergency; many women who are air raid wardens desire to carry first aid equipment, a flashlight, and other such articles in their handbags, but there are no satisfactory handbags for these purposes.

The present invention aims to provide an improved compact, relatively simple and inexpensive handbag which may be readily and easily converted so as to hold many small articles or a lesser number of large articles.

An object of the invention is to provide a new and improved pocketbook or handbag.

Another object of the invention is to provide a handbag which is easily and quickly convertible to carry different size articles.

Another object of the present invention is to provide a handbag having a removable pocket supporting and article carrying lining.

Another object of the present invention is to provide a handbag having an improved compartment that normally remains closed when another compartment is opened.

Another object of the present invention is to provide a compartment having wall portions adapted to minimize accidental collapsing or crushing together of the sides of the compartment.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming a part of the specification, wherein

Fig. 1 is a perspective view of a preferred embodiment of the invention;

Fig. 2 is a perspective view of a preferred embodiment of the invention in open position;

Fig. 3 is a rear view of a preferred embodiment of the invention;

Fig. 4 is a sectional view along the line 4—4 of Fig. 2;

Fig. 5 is an enlarged fragmentary sectional view illustrating the construction of a preferred form of removable insert member; and

Fig. 6 is a front view of a modified form of the invention.

Referring more particularly to the drawing, there is shown a handbag or pocketbook comprising a pair of adjoining main compartments 1 and 2 formed by outer side walls 4 and 5 and an intermediate wall 7. Each of these walls is preferably joined, in spaced relation, to a bottom portion 8. The walls and bottom portion may be formed from leather, fabric, or any other suitable material stitched or otherwise secured together as illustrated in Fig. 4. The outer and intermediate walls and the bottom portion are preferably stiffened with members 16 of cardboard or other suitable material; the stiffening material tends to give the walls and bottom portion sufficient rigidity so that they maintain their shapes and yet are somewhat flexible. One of the outer walls 5 preferably has an extension 11 at the upper end thereof forming a flap or cover portion, the purpose and operation of which will be hereinafter described. The other outer wall portion 4 is preferably provided with an inwardly extending flange or rim 13 at the sides and upper edge thereof, and the inwardly projecting free edge of this flange 13 is preferably provided with the teeth of a slide fastener or "zipper" adapted to interlock with cooperating slide fastener teeth.

The intermediate wall 7 is also preferably provided with a flange or rim 14 at the sides and upper edge thereof to which are secured slide fastener teeth adapted to cooperate with the teeth on the flange 13 of the outer wall 4. As the outer wall 4 and intermediate wall 7 are moved toward each other about the hinge-like bottom portion 8, the inwardly extending flange portions 13 and 14 on these wall members move toward each other until their free edges are contiguous. When the teeth at the free edges of the flange portions 13 and 14 are in this relation, a slide member 16 may be moved around the path of the cooperating teeth to lock them together into a smooth joint. The joint thus formed may be unlocked or opened by moving

the slide 16 in a reverse direction so that the walls 4 and 7 may be moved apart from each other. The inwardly facing flanges 13 and 14 on the outer and intermediate walls 4 and 7 tend to space the adjacent inward faces of these walls 4 and 7 from each other when the compartment is in closed position. This feature is desirable for it minimizes the possibility of accidentally crushing articles placed in this compartment. The inside of the above described compartment 1 may be lined with cloth 9 or any other suitable material.

It is desirable to utilize the slide fastener compartment as a multiple purpose compartment which may be used for conveniently holding a number of small articles such as nail polish, comb, nail file, tooth brush and numerous other toilet articles, and yet which may be readily converted to hold larger articles such as clothing, a book, et cetera. Preferably the compartment 1 should have numerous pockets or clips for holding small articles and should be free of any pockets or clips when holding larger articles. The compartment 1 is therefore preferably provided with a detachable pocket-carrying insert member 15. The insert member 15 may be formed by securing together layers of cloth 18, stiffening material 21, fabric 24, and oiled silk 25. The oiled silk layer 25 is preferably provided with numerous pockets 17 or flaps 19, elastic retaining loops or clips 20, and may have a mirror 22 adhesively secured thereto. The detachable insert member may be removably secured within the compartment 1 in any suitable manner; in the preferred embodiment two-part snap fasteners 23 are utilized. The snaps 23 for attaching the insert member 15 are shown located adjacent the ends of the insert member but they may be placed in other appropriate locations. The snaps 23 facilitate application and removal of the insert member 15 to and from the compartment 1. The stiffening material 21 tends to keep the insert member in shape and yet renders it sufficiently flexible. The cloth covering 18 enhances the appearance of the detachable insert member 15.

When the cooperating slide fastener teeth are unlocked and the outer wall 1 of the pocketbook allowed to lie against a supporting surface (Fig. 2) the compartment 1 simulates a small dressing table. The mirror 22 faces a user and the various toilet articles are retained readily available in the adjacent pockets or loops. When the compartment 1 is in closed position the inwardly projecting flanges 13 and 14 maintain the opposite sides of the insert member 15 spaced from each other so that bottles, jars, and other articles held by the various pockets or loops will tend to be spaced from each other. When the detachable insert member is removed from the compartment 1 the resulting relatively large compartment may be utilized for carrying a book or articles of clothing. The insert member 15 may be readily and easily attached within the compartment 1 or removed therefrom.

The intermediate wall 7 also cooperates with the other end wall 5 to form a second relatively large compartment 2. The compartment 2 may be formed by joining the side edges of the intermediate member 7 with the outer wall 5 by means of hinges or gussets 26. If desired, the edges of the gussets 26 may form the flanges or rim portions 14 located at the side of the intermediate member 7. The gussets 26 facilitate movement together and apart of the wall 5

and the intermediate wall 7. The interior of the open top compartment 2 thus formed by the walls 5 and 7 is preferably provided with a lining 28, in the general shape of a pouch, having several pockets 29 and a card or license holder 31 for carrying identification cards and the like. The lining 28 preferably has a cutout 32 therein and a pocket 33 fitted within the cutout and located between the lining 28 and outer wall 5; a slide fastener 34 may be provided at the upper edges of the cutout for opening and closing the pocket 33. A small purse 39 may be retained within the compartment 2 by means of a chain or cord 30.

It is frequently necessary to pay out small change for various items of merchandise, and it is a nuisance for women carrying several bundles to have to open a pocketbook or handbag in order to obtain this small change. The present handbag or pocketbook is therefore provided with a readily accessible pocket from which change may be extracted without the necessity of opening the entire handbag. In Figs. 3 and 4 the outer wall member 5 is illustrated provided with a cutout 35 and fitted with a slide fastener 36; a pocket 37 located at the inside of the member 5 and secured at its edges to the edges of the cutout 35 is adapted to contain change. The slide fastener 36 may be easily moved from side to side to open and close the pocket 37 so that change may be extracted from the pocket 37 without the necessity of opening and closing the entire handbag.

The extension or flap 40 at the upper end of the outer wall 5 is adapted to fold over the top of the open compartment 2 and also over the top of the compartment 1 when the device is carried in closed position. The flap 40 closes the compartment 2 to prevent loss of articles therefrom and gives the handbag a beautiful finished appearance. Preferably the flap 40 has an aperture 41 therein surrounded by a relatively large eyelet 43. The eyelet is adapted to fit over a projecting member 44 secured to the opposite wall member 4 and to snap over resilient pins or ball members 46 carried by the projecting member 44. When the flap 40 is thus snapped over the resilient members 46 the flap will be retained securely in position against accidental opening and spilling of articles out of the compartment 2. Handle members or straps 48 may be secured adjacent their ends to the outer sides of wall members 4 and 5 by sewing or otherwise.

In Fig. 6 there is illustrated a modified form of the present invention wherein a strap or handle member 50 extends completely under and around the handbag. The strap 50 is preferably a single continuous one and extends through loops 51 located at each side of the handbag. Also, the flap 40a of the handbag illustrated in Fig. 6 is not provided with the cooperating recess and resilient locking members of the preferred embodiment; instead the portions of the strap 50 which extend along the outer surface of the flap 40a are depended upon to retain the flap in closed position over the tops of the compartments.

It will be seen that the present invention provides a new and improved handbag or pocketbook which is adapted to serve a variety of uses. The various features provide a highly useful combination device. A detachable member may be utilized for carrying various toilet articles in readiness for immediate use at all times and may be easily and quickly removed to provide a compartment for transporting larger articles. A readily

accessible change pocket eliminates the necessity for opening the entire bag in order to obtain small change.

As various changes may be made in the form, construction and arrangement of the parts herein without departing from the scope and spirit of the invention and without sacrificing any of its advantages, it is to be understood that all matter herein is to be interpreted as illustrative and not in a limiting sense.

Having thus described my invention, I claim:

1. In a handbag, the combination of an open-top compartment, means for closing the open top of the compartment, a double compartment coin purse secured to one side of the open top compartment, said compartments opening upwardly, closing means permitting access to one compartment of the purse from the inside of the open-top compartment, a slit in the side of the open-top
- 5 compartment permitting access to the other purse compartment while the handbag is closed and means for opening and closing said slit.
- 10 2. In a handbag, the combination of an open-top compartment, means for closing the open top of the compartment, a coin purse secured to one side of the open top compartment having a middle portion therein to form two compartments, said two compartments in the coin purse opening upwardly, closing means permitting access to one compartment of the purse from the inside of the open top compartment, a slit in the side of the open top compartment permitting access to the other purse compartment while the handbag is closed, said portion in the coin purse preventing access to the inside of the open top compartment through said slit and means for opening and closing said slit.

VIOLET E. OHLSEN.
